EMIL SCHNEEBELI, OF AFFOLTERN-ON-THE-ALBIS, SWITZERLAND.

MACHINE FOR DRESSING OR FINISHING SILK STUFFS.

1,130,846.

Specification of Letters Patent.

Patented Mar. 9, 1915.

Application filed June 12, 1914. Serial No. 844,820.

To all whom it may concern:

Be it known that I, EMIL SCHNEEBELI, a citizen of the Republic of Switzerland, residing at Affoltern-on-the-Albis, in the Canton of Zurich, Republic of Switzerland, have invented certain new and useful Improvements in Machines for Dressing or Finishing Silk Stuffs; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has for its object to provide an improved machine for dressing or finishing silk stuffs which machine preserves the freshness, the feel and the luster or gloss of the fabrics treated, shortens the time required for the finishing process, and further renders possible the employment of different methods of treatment. For the purpose of attaining this object the fabric is caused to pass through two superposed devices for spraying two different compositions on the fabric, which latter then passes through a drying box, in which its two sides are exposed to the drying action of a current of air flowing in a direction opposite to that of the travel of the fabric, and finally during the same travel of the fabric through the machine, the said fabric passes through the finishing elements, such as breaking rollers and calenders.

The separate devices which the improved dressing or finishing machine comprises, such as the rollers and the nozzles for applying the dressing or the like, the drying box, the breaking rollers and the calender rollers, are of the usual design commonly adopted in the art. Whereas, however, it was necessary hitherto that the fabric should traverse several machines, for the purpose of receiving a complete finish, the fabric according to this invention need traverse the improved machine, in which the separate devices are arranged and combined in a suitable manner, only once for the purpose of receiving a complete finish. By employing the improved machine it is therefore possible to effect a considerable saving in the cost of manufacture, the time required for the finishing process, the working expenses, the attendance and the space required by the machine. As the fabric need

pass through the machine only once, the same retains its freshness, its feel and its luster or gloss, whereas silk stuffs which have to traverse several machines in succession, lose the aforesaid properties to a large extent and consequently deteriorate in value.

The improved machine, which is to be used chiefly for treating silk stuffs, may be employed in a variety of ways, namely for dressing, drying, breaking, calendering and rebreaking, or for dressing and drying, or for dressing and hot calendering, or for cold calendering or hot calendering alone, or for moistening and calendering. The superposing of the spraying devices renders possible to spray simultaneously different dressing compositions on the fabric, which compositions cannot be mixed together, the application of which, however, is necessary for insuring a perfect finish. By means of the current of drying air accurately following the zigzag course taken by the fabric to be dried, but moving in opposite direction thereto, and uniformly passing over the two sides of the fabric, a drying effect of any desired degree may be obtained, and thus the fabric may be allowed to issue from the drying box at any desired rate which is required by the succeeding calender. This effect cannot be obtained with the existing drying contrivances working with or without the use of the counter-current principle.

The improved machine may be employed with particular advantage by the manufacturer or weaver, since by means of the same he is enabled to finish the fabric himself. Further the dressing composition may be applied without artificial heating and cold air may also be used for drying.

One form of carrying the invention into effect is shown diagrammatically in the accompanying drawing, by way of example.

In carrying the invention into effect as shown in the drawing, the fabric 2 passes from an unwinding roller 1 over a supporting roller 3, and over a wire netting, which is not shown in the drawing and which serves for preventing the fabric, when torn, from dropping down into the gear, to a guide roller 4, at the opposite end of the machine. At this roller 4, the direction of travel of the fabric web is changed from horizontal to vertical. In this vertical direction of travel the fabric traverses two

spraying chambers 5 and 6, in which the dressing composition is sucked up in a known manner by spraying nozzles 7 and 8, and is applied to the fabric 2. The object 5 of these two spraying chambers is to enable one to apply to the fabric two different compositions which cannot be used together in one solution, and which are necessary for imparting certain properties to the fabric. 10 From the spraying chambers, the fabric passes over a guide roller 9 into a drying chamber 12 of ordinary design, and provided with partitions or baffles 10 and 11, in which drying chamber a considerable 15 length of the fabric is exposed to the action of a current of air moving in counter-direction to the travel of the fabric and heated to suit the particular requirements of each case. Of the guide rollers 13-28, the roller 20 14 is connected to the counter shaft 27 by means of a belt drive 24, 25, 26, which counter shaft 27 is driven from the shaft 28.

Into the right hand end of the drying chamber 12 there opens a pipe 29 through 25 which hot air to be used for drying is supplied, which air leaves the drying chamber at the opposite end through a pipe 30. Owing to the fact that the fabric traversing the drying chamber encounters a hot current 30 of air moving in the opposite direction to the travel of the fabric, a rapid drying is the result. The current of drying air accurately following the zigzag shaped course taken by the fabric to be dried, but moving 35 in an opposite direction thereto and uniformly passing over both sides of the fabric, renders possible any desired degree of drying, so that the fabric may be allowed to leave the drying box at any desired speed 40 which may be required by the succeeding calender. From the drying chamber, the fabric passes over a guide roller 31 to the roller 33 which is driven from the roller 14 by means of a belt 32, and from there to a 45 pair of breaking rollers 34, 35 of ordinary design, which latter may be moved if required. Thereafter the fabric 2 passes over a guide roller 36 to two calender rollers 37, 38, which are of usual design and of which 50 the upper roller is pressed against the lower roller by the action of its own weight and the pressure exerted by the adjustable weight 39, the said roller, however, may be relieved of the pressure exerted by the 55 weight 39, in a known manner, by means of the hand operated lever 40, the cam 41,

and intermediate connecting rods. From the calender rollers which impart to the fabric any desired degree of luster or gloss, the fabric passes over a known drawing 60 roller 44 mounted on levers 42 and moved upward by a weight 43, and from there to a winding up roller 46, driven by means of belts 45 from the shaft 27, and arranged above the unwinding roller 1. If necessary 65 the fabric, before being wound up, may be passed over a second pair of breaking rollers 47, 48.

If the fabric is only to be moistened, it is allowed to pass from the guide roller 9 over 70 five guide rollers 49, 50, 51, 52 and 48 to the drawing roller 44, thus by-passing the drying chamber 12.

The calender rollers are driven by a toothed gear wheel train 53, 54, 55, 56 75 and 57.

If required, the fabric may be sprayed with dressing on both sides, for which purpose two spraying nozzles are arranged in each chamber 5 and 6. Further the fabric, 80 before entering the spraying chambers 5 and 6, may pass over rollers 58, 59 and 60, and be provided with dressing liquor by means of a roller 61 or by means of brushes.

What I claim is:—

1. A machine for dressing or finishing silk stuffs comprising in combination means for spraying dressing compositions on to the fabric consisting of two superposed chambers through which the fabric moves 90 vertically, nozzles arranged within said chambers, a drying box, finishing elements, and means for moving the fabric successively to the various devices.

2. A machine for dressing or finishing 95 silk stuffs comprising in combination means for spraying dressing compositions on to the fabric, a drying box having a zig-zag passage and means for guiding the fabric therethrough, means for causing two independent streams of air to pass one on each side of the fabric in the opposite direction to its travel, finishing elements for said fabric, and means for moving the fabric successively to the various devices.

In testimony whereof, I have signed my name to this specification in the presence of two subscribing witnesses.

EMIL SCHNEEBELI.
